UNITED STATES PATENT OFFICE

2,423,041

DENTAL CROWN CAP PRESS

Anton F. Miskunas, Chicago, Ill.

Application March 15, 1946, Serial No. 654,581

3 Claims. (Cl. 113—39)

1

My invention relates to appliances employed in mechanical dentistry, and more particularly to presses for forming dental crown caps. These have a prescribed formation for every type of tooth, and it is one object of the present invention to provide a press having a series of units for the simultaneous formation of a set of caps of the conventional types, such as for bi-cuspids, molars, etc.

A further object is to provide a press of the above character which separates the forming units for upper crown caps from those for lower crown caps to avoid confusion.

Another object is to provide a crown cap press which operates on the double-throw principle, whereby to form upper crown caps by an action in one direction and lower crown caps by an action in the opposite direction.

An important object is to construct the press along lines of ruggedness and extreme simplicity.

With the above objects in view and any others which may suggest themselves from the description to follow, a better understanding of the invention may be had by reference to the accompanying drawing, in which—

Fig. 1 is an elevation, partly in section, of the novel press as applied in one direction, dotted lines showing its application in the opposite direction;

Fig. 2 is an enlarged end view from the right-hand portion of Fig. 1, and partly in section on the line 2—2 of the same figure; and

Fig. 3 is an enlarged section on the line 3—3 of Fig. 1.

In accordance with the foregoing, specific reference to the drawing indicates the base of the press at 10, the same being a casting of bronze or other hard metal. The base is of elongated formation and rises in the middle with an integral standard 11, which extends crosswise of the base and is of the same width, as shown in Fig. 3. The base is extended endwise with perforated lugs 10a for screws to secure the base on a bench or other support.

The standard 11 is cut down from the top in two places—one being indicated at 12 in Fig. 2—to define three alined bars 13; and the spaces 12 are designed to receive the ears 14 extending from the corresponding end of a massive rectangular block 15. A pintle 15a is passed through the ears 13 and 14 to dispose the block 15 in pivotal relation to the standard 11. The block 15 is extended outwardly with an arm 16; and the latter terminates with a looped handle 17.

The block 15 is formed with a pair of ribs 18

on each side, these extending longitudinally near the side edges of the block. The ribs 18 on one side are extended with a longitudinal series of punches 19, these having terminal formations 20 suitable for impressing gold crown cap blanks (not shown) with the proper or prescribed forms to suit upper bi-cuspids, molars, etc. The cross-sectional form of the punches 19 is circular, oval or otherwise elongated, according to the shape of the terminal profile.

When the block 15 is positioned as shown in Fig. 1, the punches 19 on its under side press the cap sheets into matching indentations 21 in the top surface of the base, so that the caps 15 are formed when the block is applied with pressure on the handle 17. However, when the block is swung in the direction of the arcuate arrow in Fig. 1 to assume the dotted line position a like set of punches 22 with terminal formations 23 and extending toward indentations 24 to shape caps for lower teeth functions in the same manner between the other side of the block and the corresponding part of the base.

The novel press, as described above, has a number of advantageous features. First it combines in a single, compact structure a complete set of forming units or dies for all the crown cap formations required. Further, the press is divided to locate the units for upper teeth separate from those for lower teeth, eliminating the prospect of confusion in this respect. Further, a single, sturdy member carries all the punches and is capable of being economically cast in one piece. Further, the said single member is capable of forming either set of caps by utilizing the double-throw principle, the pivotal attachment of such member in the center of the base leaving the adjacent surfaces of the same clear and accessible to the corresponding punches when the 40 member is applied accordingly. Finally, the novel press is only made with two major parts and of sufficient strength to serve its purpose efficiently.

While I have described the invention along specific lines, various minor changes or refinements 45 may be made therein without departing from its principle, and I reserve the right to employ such changes and refinements as may come within the scope and spirit of the appended claims.

I claim:

50 1. A dental crown cap press comprising an elongated base with a standard in the center, the top surface of the base on one side of the standard having a series of indentations corresponding in formation to crown caps for upper teeth and on the other side a series of indentations

corresponding in formation to crown caps for lower teeth, and a member connected to the standard for movement in the direction of either series of indentations, such member presenting punches in either case matching and directed toward the related indentations.

2. The structure of claim 1, said member being pivoted to the standard to be swingable alternately toward either series of indentations with said punches extending from the sides of the member facing the corresponding series.

3. The structure of claim 1, the standard extending transversely of the base, said member being horizontally pivoted to the standard to be swingable alternately toward either series of indentations with said punches extending from the

sides of the member facing the corresponding series, and a handle extending outwardly from the member.

ANTON F. MISKUNAS.
